UNITED STATES PATENT OFFICE.

GEORGE HOFMANN, OF LYONS, ILLINOIS.

FURNACE.

Application filed January 19, 1927. Serial No. 162,066.

My invention relates more particularly, though not exclusively, to oil-fired furnaces and one of my objects, generally stated, is to provide improvements in furnaces to the end that more nearly complete combustion of the fuel, especially in oil-fired furnaces, will be effected in the use of either "distillate" or "gas oil", the production of free, unconsumed, carbon and the coating of the heating surfaces of the furnace with soot, which, if present, insulates the heating of the surfaces from the burning fuel with resultant loss in effectiveness of the fuel for the intended purpose, will be practically prevented and loss due to waste of fuel greatly reduced. Another object is to provide for the utilization, to as near the maximum extent as possible, of all of the heat units generated by the combustion of the fuel particularly in the heating of water in a boiler-furnace. Another object is to provide for the rapid heating of water in a boiler furnace particularly in a steam-boiler, with the minimum consumption of fuel; and other objects as will be manifest from the following description:

Referring to the accompanying drawings:

Figure 1 is a view in front elevation of a boiler furnace constructed in accordance with my invention, a portion of the front thereof being broken away to disclose interior details. Figure 2 is a view in side elevation of the furnace with a portion of the side thereof broken away. Figure 3 is a view in longitudinal sectional elevation of a flame-deflecting and primary water-heating element of the furnace. Figure 4 is a section taken at the line 4—4 on Fig. 3 and viewed in the direction of the arrows. Figure 5 is a section taken at the line 5—5 on Fig. 3 and viewed in the direction of the arrows; and Figure 6, a perspective view of the structure of Figs 3, 4 and 5.

Inasmuch as I have devised my invention for use more especially in a boiler-furnace I have chosen to illustrate it in such a structure, which is shown as a steam-boiler having a combustion chamber represented at 10 and containing an opening in the front wall 50 of the furnace, equipped with a door 11, and

an outlet 12 for the products of combustion in the rear wall of the furnace adjacent the top of the chamber 10. The furnace, which as to its general features of construction is of a common and well-known type, is also provided with water-chambers formed in the several flatwise-assembled grid-like sections 13, of the furnace the chambers in which open, respectively, into pipes 14 communicating with a header 15 from which the steam-pipe 16 extends. The lower ends of the sections 13 form the upper portion of the combustion chamber 10, the intermediate ones of these sections having leg-portions 13^a which form portions of the side-walls of the combustion chamber 10, as shown in Fig. 1, with the water-chambers in these sections extending downwardly close to the bottom surfaces of these legs. The sections 13 are shown as supported on a rectangular base 17 of concrete which forms the lower portions of the surrounding walls of the combustion chamber 10, the opposite side walls of this chamber from the bottom of the furnace to a point about half-way to the top of this chamber, and preferably throughout the length of the latter, being of upwardly and outwardly-curved form, as shown at 18, such surfaces being preferably provided by lining the side walls of the base 17 with refractory material 19 as shown.

Located in the combustion chamber 10, in a position to extend into the path of the combustion mixture in flowing in the combustion chamber, is a combustion mixture deflecting and primary water-heating device represented generally at 20, which extends lengthwise of the chamber 10 and at its sides, top and bottom in spaced relation to the opposing surfaces of this chamber, the front-end portion of the device 20 being in line with the inlet 21, through which the combustion-mixture, as for example atomized oil, is introduced into the combustion chamber 10, the mixture burning upon issuing from the inlet and as it moves along the deflector device 20.

The device 20 which, in the particular arrangement shown, is provided as a structure separate from the furnace proper and would

be so provided especially when it is desired to equip existing furnaces with the invention, but which in the case of original installations could be built into the furnace 5 otherwise than as a separate part, is formed of a hollow body 22 of general semi-cylindrical form with its curved surface uppermost, as shown, and arranged in the chamber 10 to extend substantially horizontally 10 therein, the body 22 having a depending hollow fin 23, the space in which opens into the space within the body 22 as shown in the drawings, thereby forming a water-chamber 24 in the body 22 extending downwardly 15 into the fin 23 throughout substantially the length of the latter.

The fin 23 which is disposed substantially vertically and is located mid-way between the opposite sides of the body 22, inclines 20 at its bottom edge-portion upwardly and rearwardly, as shown, the forward extremity of the fin, which is in direct alignment with the fuel-inlet 21, being relatively thin and presenting substantially parallel vertical side surfaces 25. The side-surfaces of 25 the fin, from the front end thereof toward its rear end, are outwardly curved, as represented at 26, with progressively increasing curvature, to a point at the extreme rear end 30 of the fin 23, where the fin substantially merges into the flat horizontal bottom of the body portion 22, as clearly shown in the drawings.

The water-chamber 24 is connected at 35 its forward end with a pipe 27, constituting a part of the piping through which the water condensed in the heating pipes of the heating system in connection with which the boiler would be used, is returned to the boiler, the pipe 27 being shown as connected at 28 with piping 29 which opens into the lower ends of the legs 13^a, the piping 29 connecting with a pipe 30 through which the return-water flows to piping 29. The 45 rear end of the water-chamber 24 communicates, at its upper portion, with one end of a pipe 31 which opens at its other end into the water-chamber of the boiler preferably below the water-level maintained in the 50 boiler.

In the operation of the furnace the combustion-mixture discharges into the combustion chamber 10 through the inlet 21, the mixture being ignited as it leaves the inlet, 55 and by reason of the position of the fin 24 directly in line with the inlet, is caused to be divided by the fin into two separate streams which, in traversing the increasing- 60 ly-curving side-surfaces of the fin, are deflected laterally and outwardly toward opposite sides of the combustion chamber and thereafter toward the median line of the device 20 and to the outlet 12 as represented generally by the arrows in Figs. 1 and 2, 65 with the result of causing all of the fuel to

be consumed, without release of free, unconsumed, soot-forming carbon. The burning combustion-mixture by reason of the curvature of the sides of the fin, the curved top of the device 20 and the curved side walls 70 19 flows laterally outwardly in impinging against the outwardly curving surfaces of the underside of the device 20, and thence flows upwardly in a direction from opposite sides of the device 20 toward the median 75 line of the latter and in sweeping over the top of the device 20 and closely adjacent thereto ignites such of the mixture as in un-ignited condition flows up and around the device 20 in close proximity thereto, the various curvatures provided to the several surfaces referred to, being preferably such as shown, that no abrupt deflections of the stream of combustion-mixture occur, such as would have a tendency to materially interfere 80 with a natural stream-line flow.

While a furnace structure providing the deflecting surfaces as described has advantage in structures in general wherein complete combustion of fuel is desired, it is of 90 particular importance where the body 20 is provided as a hollow structure, as shown and described, and forms a container for water to be heated in the furnace. By such an arrangement not only is the heating surface 95 contacted by the water to be heated greatly increased over the surface presented by the combustion chamber of the ordinary furnace, but by the provision of the hollow body 20, which is substantially submerged 100 in the flame produced by the burning combustion-mixture, the relatively cold water entering the furnace is subjected to a large body of flame of relatively great intensity with the manifest advantage. Furthermore by the arrangement shown the flame is deflected against the lower portions of the water-chambers of the furnace, viz, those in the legs 13^a, to greatly aid in the utilization of the heat of the burning fuel and which differs from the ordinary construction of boiler-furnace wherein the intake is the least heated of any part of the heated-water course and is dependent for its heating primarily by the heat transmitted to it from 110 the top of the boiler.

While I have illustrated and described a particular construction embodying my invention, I do not wish to be understood as intending to limit it thereto as the same may 120 be variously modified and altered without departing from the spirit of my invention, and in this connection, and by way of example, the form of the device 20 may be varied, if desired, and may be provided as a 125 structure built into the furnace instead of providing it as a separate part.

What I claim as new, and desire to secure by Letters Patent, is:

1. A furnace comprising a combustion 130

chamber, a deflector located in said chamber, and means for supplying a combustion mixture to said chamber and causing it to flow substantially horizontally therein, the longitudinal axis of said deflector extending generally in the direction of said flow of the combustion mixture, said deflector having an under surface disposed in the line of said flow and so shaped as to cause the mixture engaging said deflector to be deflected laterally in opposite directions toward the side walls of said chamber.

2. A furnace comprising a combustion chamber, a combined water container and combustion-mixture-deflecting member located in said chamber, and means for supplying a combustion mixture to said chamber and causing it to flow substantially horizontally therein, the longitudinal axis of said member extending generally in the direction of said flow of the mixture, said member having an under-surface disposed in the line of said flow and so shaped as to cause the mixture engaging said member to be deflected laterally in opposite directions toward the side walls of said chamber.

3. A furnace comprising a combustion chamber, a combined water container and combustion-mixture-deflecting member located in said chamber, and means for supplying a combustion mixture to said chamber and causing it to flow substantially horizontally therein, the longitudinal axis of said member extending generally in the direction of said flow of the mixture, said member having an under-surface disposed in the line of said flow and upwardly and outwardly inclined at opposite sides of its axis for deflecting the mixture laterally outwardly in opposite directions toward the side walls of the chamber.

4. A furnace comprising a combustion chamber, a combined water container and combustion-mixture-deflecting member located in said chamber, and means for supplying a combustion mixture to said chamber and causing it to flow substantially horizontally therein, the longitudinal axis of said member extending generally in the direction of said flow of the mixture, said member having an under-surface disposed in the line of said flow and presenting concave surfaces of progressively decreasing curvature from the forward end of said member toward the rear end thereof.

5. A furnace comprising a combustion chamber, a combined water container and combustion-mixture-deflecting member located in said chamber, and means for supplying a combustion mixture to said chamber and causing it to flow substantially horizontally therein, the longitudinal axis of said member extending generally in the direction of said flow of the mixture, said member presenting a substantially vertical-

ly disposed fin extending lengthwise of said member and substantially horizontally disposed surfaces extending in opposite directions from said fin and disposed in the line of said flow, the side surfaces of said fin and said substantially horizontally disposed surfaces progressively curving from the front end of said member toward the opposite end thereof and toward a condition of merger into alignment with each other.

6. A furnace comprising a combustion chamber, a combined water container and combustion-mixture-deflecting member located in said chamber, and means for supplying a combustion mixture to said chamber and causing it to flow substantially horizontally therein, the longitudinal axis of said member extending generally in the direction of said flow of the mixture, said member presenting a substantially vertically disposed portion extending lengthwise of said member and disposed in the line of said flow and concave surfaces extending lengthwise of the deflector at the opposite sides of the plane of said vertically disposed portion and also disposed in the line of said flow and progressively curved from the front end of said member toward its opposite end and operating to deflect the mixture laterally outwardly toward opposite sides of said chamber.

7. A furnace comprising a combustion chamber, a combined water container and combustion-mixture-deflecting member located in said chamber, and means for supplying a combustion mixture to said chamber and causing it to flow substantially horizontally therein, the longitudinal axis of said member extending generally in the direction of said flow of the mixture, said member being formed of a body portion of general semi-cylindrical form with a depending fin portion extending lengthwise of said body portion and disposed in the line of said flow, the under surface of said member at opposite sides of said fin, and also disposed in the line of said flow, presenting concave surfaces of progressively increasing curvature from the front portion of said member toward the opposite end portion thereof and operating to deflect the mixture laterally outwardly toward opposite sides of said chamber.

8. A furnace comprising a combustion chamber having upwardly and outwardly curved side walls, means for supplying a combustion mixture to said chamber and causing it to flow substantially horizontally therein, and means extending into the line of flow of the mixture for deflecting the mixture laterally and outwardly toward and against said curved side walls along a substantial length thereof.

9. A furnace comprising a combustion chamber having upwardly and outwardly

curved side walls, a deflector located in said chamber, and means for supplying a combustion mixture to said chamber and causing it to flow substantially horizontally therein, the longitudinal axis of said deflector extending generally in the direction of said flow of the combustion mixture, said deflector having an under surface disposed in the line of said flow and so shaped as to cause the mixture engaging said deflector to be deflected laterally in opposite directions toward and against said curved side walls along a substantial length thereof.

10. A furnace comprising a combustion chamber having upwardly and outwardly curved side walls, a combined water container and combustion-mixture-deflecting member located in said chamber, and means for supplying a combustion mixture to said chamber and causing it to flow substantially horizontally therein, said member extending into the line of flow of the mixture and operating to deflect the mixture laterally outwardly toward and against said curved walls along a substantial length thereof.

11. A furnace comprising a combustion chamber having upwardly and outwardly curved side walls, a combined water container and combustion-mixture-deflecting member located in said chamber, and means for supplying a combustion mixture to said chamber and causing it to flow substantially horizontally therein, said member extending into the line of flow of the mixture with its under surface so shaped as to cause the mixture engaging said member to be deflected laterally outwardly in opposite directions toward and against said curved walls along a substantial length thereof.

12. A boiler furnace comprising a combustion chamber, a combined water container and combustion-mixture-deflecting member located in said combustion chamber and communicating with the main water chamber of the boiler, and means for supplying a combustion mixture to said chamber and causing it to flow substantially horizontally therein, the longitudinal axis of said member extending generally in the direction of said flow of the combustion mixture, said member having an under surface disposed in the line of said flow and so shaped as to cause the mixture engaging said member to be deflected laterally in opposite directions toward the side walls of said chamber.

13. A boiler furnace comprising a combustion chamber having upwardly and outwardly curved side walls, a combined water container and combustion-mixture-deflecting member located in said chamber and in communication with the main water chamber of the boiler, and means for supplying a combustion mixture to said chamber and causing it to flow substantially horizontally therein, the longitudinal axis of said member extend-

ing generally in the direction of said flow of the combustion mixture said member having an under surface disposed in the line of said flow and so shaped as to cause the mixture engaging said member to be deflected laterally outwardly in opposite directions toward and against said curved side walls.
